US0D1081045S

(12) **United States Design Patent** (10) Patent No.: **US D1,081,045 S**
Chen et al. (45) Date of Patent: ** Jun. 24, 2025

(54) **VACUUM CLEANER**

(71) Applicant: **DO-IT INNOVATIONS TECHNOLOGY CO., LTD.**, Zhuhai (CN)

(72) Inventors: **Xiaoling Chen**, Zhuhai (CN); **Yunpeng Hu**, Zhuhai (CN); **Shaochun Tian**, Zhuhai (CN)

(73) Assignee: **DO-IT INNOVATIONS TECHNOLOGY CO., LTD.**, Zhuhai (CN)

(**) Term: **15 Years**

(21) Appl. No.: **29/925,531**

(22) Filed: **Jan. 24, 2024**

(51) LOC (15) Cl. **15-05**

(52) U.S. Cl. USPC **D32/21**

(58) **Field of Classification Search**

USPC ..... D15/199; D21/526, 578; D32/15, 16, D32/17, 18, 21, 23, 25, 29, 30, 31, 38, 39 CPC A47L 5/00; A47L 5/12; A47L 7/00; A47L 7/0004; A47L 7/0019; A47L 7/0023; A47L 11/00; A47L 11/22; A47L 11/24; A47L 11/32; A47L 11/33; A47L 11/4094

(57) **CLAIM**

The ornamental design for a vacuum cleaner as shown and described.

DESCRIPTION

FIG. 1 is a front, right and top perspective view of a vacuum cleaner, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the vacuum cleaner that form no part of the claimed design.

1 Claim, 8 Drawing Sheets
